UNITED STATES PATENT OFFICE

139,720

DESIGN FOR A MOTOR FOR OPERATING MOVABLE PARTS OF AN AIRPLANE

Ralph M. Heintz, Cleveland, Ohio, assignor to
Jack & Heintz, Inc., Bedford, Ohio, a corpora-
tion of Ohio

Application September 18, 1944, Serial No. 115,350

Term of patent 14 years

(Cl. D26—5)

To all whom it may concern:

Be it known that I, Ralph M. Heintz, a citizen of the United States, residing at Cleveland, in the county of Cuyahoga and State of Ohio, have invented a new, original, and ornamental Design for Motor for Operating Movable Parts of an Airplane, of which the following is a specification, reference being had to the accompanying drawings, forming part thereof, wherein:

Figure 1 is a side elevational view of a motor for operating movable parts of an airplane showing my new design.

Figure 2 is a side elevational view taken at right angles to Figure 1.

Figure 3 is an end elevational view looking at the base of the motor for operating movable parts of an airplane, and

Figure 4 is an end elevational view of the opposite, or head, end.

I claim:

The ornamental design for a motor for operating movable parts of an airplane, substantially as shown.

RALPH M. HEINTZ.
